Atty.

UNITED STATES PATENT OFFICE.

CHARLES T. DAVIS, OF BALTIMORE, MARYLAND, ASSIGNOR TO GEORGE V. KEEN, JAMES S. HAGERTY, AND JAMES R. HAGERTY, ALL OF SAME PLACE.

WATER-EVAPORATOR FOR STOVES.

SPECIFICATION forming part of Letters Patent No. 309,772, dated December 23, 1884.

Application filed January 23, 1884. (No model.)

To all whom it may concern:

Be it known that I, CHARLES T. DAVIS, of the city of Baltimore and State of Maryland, have invented certain Improvements in Water-Evaporators for Stoves, of which the following is a specification.

In carrying out my invention I apply to a stove in various ways an open vessel containing water, having thimbles therein, through 10 which heat radiated from the stove passes to the apartment. The evaporator is not in full contact with the heated surface of the stove, but is provided with flanges or projections, which serve to insulate the vessel, and thereby 15 prevent direct conduction of heat to the water. By this isolation of the vessel the water is less liable to boil and give off a superabundance of steam or vapor. The flanges also serve to provide a hot-air chamber between the evaporator and the stove, from which the heated 20 air passes uniformly through the thimbles to the apartment.

In the further description of my invention, reference being had to the accompanying 25 drawings, forming a part hereof, in which—

Figure I is a perspective view of a stove provided with my improved evaporator. Fig. II is a vertical section of my evaporator and portions of the stove on an enlarged scale. 30 Fig. III is a top view of the evaporator, also on an enlarged scale. Fig. IV is a partly-sectional view of an evaporator modified in construction, and illustrating a different mode of applying the invention to a stove. Figs. V and VI are exterior views, as seen from 35 different points, of an evaporator adapted for application to a flat surface of a stove.

A is the stove proper, and B the water-evaporator, which in Figs. I, II, and III consists of a shallow cylindrical pan, *a*, having a 40 central opening, *b*, for the escape of vapor, and thimbles *c*, for the passage of heated air

from the stove to the apartment. In the said figures the evaporator is constructed so as to be applicable to the top of the stove, and when 45 so applied it is preferably covered by an ornamental perforated cover, C, which admits of the escape of the moistened air to the surrounding atmosphere. A flange, D, which surrounds the bottom *e* of the evaporator, forms, 50 in connection with the said bottom and the stove-top *f*, a chamber for hot air, and also serves to isolate the vessel from the hot plate *f*, and prevent the too rapid heating of the water. 55

In Fig. IV the evaporator is in the form of a jacket which surrounds a part of the stove-cylinder.

The evaporator shown in Figs. V and VI is flat, and adapted for application to a stove 60 having a similar surface.

I disclaim in this case the invention described by me in an application for Letters Patent for an improvement in hot-air registers and water-evaporators, filed January 23, 65 1884, under No. 118,405.

I claim as my invention—

1. As a new article, a water-evaporator adapted for application to a stove, which consists of a vessel with an open top, having the 70 front and rear sides perforated, and connected by thimbles which are inserted in the said perforations, substantially as specified.

2. In combination with a stove, a water-evaporator having an opening at the top, 75 thimbles extending through it for the passage of hot air, and a flange to separate the evaporator from the surface of the stove, and thereby form a chamber for hot air, substantially as specified.

CHAS. T. DAVIS.
